UNITED STATES PATENT OFFICE.

JOHN HOLTZMAN AND ABRAHAM GEFFON, OF NEW YORK, N. Y.

COMBINED SAFETY-RAZOR AND RAZOR-BLADE SHARPENER.

1,200,728.

Specification of Letters Patent. Patented Oct. 10, 1916.

Application filed May 12, 1915. Serial No. 27,498.

To all whom it may concern:

Be it known that we, JOHN HOLTZMAN and ABRAHAM GEFFON, residents of the city of New York, in the county of New York and

5 State of New York, have invented a certain new and useful Combined Safety-Razor and Razor-Blade Sharpener, of which the following is a specification.

This invention relates to safety razors, and 10 its principal object is to provide a simple, inexpensive, efficient, and improved safety razor having combined therewith simple, inexpensive, efficient and improved means for sharpening the razor blade thereof. 15 And a further object is to provide an improved safety razor, the parts of which may be rapidly and conveniently taken apart for cleaning or other purposes.

Other objects and advantages will here- 20 inafter appear.

In the accompanying drawings, Figure 1 is a general end view of the safety razor. Fig. 2 is a sectional side elevation of the razor shown in Fig. 1. Fig. 3 is a sectional 25 plan view of the razor, taken on the line $x-x$ of Fig. 1. Fig. 4 is a side elevation showing the razor converted into a sharpening machine for its blade. Fig. 5 is an end elevation of the converted razor showing it 30 in operative position for sharpening the blade. Fig. 6 is a fragmentary view of one of the details of the safety razor.

A double-edged razor-blade 1 is placed in proper disposition upon a guard 2 for its 35 edges 1^a, and a holding plate 3 is provided with a pair of pronged projections 4 which pass through openings 5 in said blade, arranged along its center line, and also through registering openings 6 in said 40 guard. An independent razor-handle 7 consists of an exterior tube 7^a having therewith in a forked flat metal spring 8 the ends of which project beyond the extremity 9 of said tube and form thereat extensions 10 by means of which the spring 8 is retained 45 in place in connection with said tube. Upon pressing said buttons inwardly toward each other the extensions 10 may be made to move toward one another while releasing of said buttons causes said extensions to move away 50 from each other to the position shown in Fig. 2. The extensions 10 are provided with

openings 12 which are adapted to slip over the heads 13 of projections 4 when the buttons 11 are pressed to move said extensions toward each other, and when they thus slip 60 over said projections and the buttons are released the edges 12^a of said openings spring over to and engage the projections 4 at the interior sides of the heads 13 and thereby secure together the blade 1, guard 2, 65 holding-plate 3, and the handle 7, rendering the safety razor in this manner completely assembled, Figs. 1, 2, and ready for shaving. Should it be desired to disassemble the parts constituting the safety razor for clean- 70 ing or other purposes it merely requires pressing of the buttons 11 inwardly and simultaneously withdrawing the handle 7 away from the projections 4, whereupon all of the aforementioned parts at once become 75 separated and may be taken apart.

To the razor blade 1 and along the center line thereof is secured a bar 14 by means of a screw 15 passing through a central opening in the blade threading into the bar, and 80 said bar is provided with openings 16 registering with the razor-openings 5 to permit passage of projections 4 therethrough. At the extremities 17 of bar 14 is pivoted a frame 18 comprising arms 19 that are pivoted to and extend from said extremities and a cross bar 20 connecting said arms. Upon the underside of cross-bar 20 are located headed projections 21 which are similar in configuration and disposition to the 85 above described projections 4. When it is necessary to sharpen the edges 1^a of the razor-blade 1 the handle 7 is disengaged from the projections 4 and the holding-plate 3 with the guard 2 are entirely removed 90 from the blade 1, and then the handle is engaged with the projections 21 of frame 18. Thereupon the safety razor is converted into a sharpening machine comprising as its chief parts the handle 7, the frame 18 mounted rigidly thereon, and the blade 1 mounted 95 pivotally in said frame. A retaining strap 22 bent around one of the arms 19 and slideable therealong may be slipped over the razor-blade 1, in the manner shown in Figs. 100 1, 6, to prevent rotation or swinging of the blade and retain it disposed in the general direction of the longitudinal axis of handle 7. After thus steadyng the razor-blade 1 105 its edge 1^a may be sharpened with the machine by moving it along a sharpening surface 23 of a stone or strap, and the blade is 110

maintained during sharpening in proper position angularly to the surface 23, Fig. 5, by means of guiding rollers 24 mounted in ears 25 secured to the handle-tube 7^a. After one side of one of the edges 1^a has been sharpened the machine may be turned around oppositely and the opposite side of said edge sharpened therewith, and after the sharpening of said edge has been completed the blade may be turned around in the machine and its opposite edge similarly sharpened. All that it requires to turn the blade around in the frame 18 is the sliding away therefrom of the retaining strap 22, swinging 15 around of the blade half a revolution, and then sliding back the strap 22 over the blade to steady it in sharpening position. When sharpening or honing the blade against a stone the machine is moved therealong in a direction which is toward the blade, and when stropping the blade the machine is moved in an opposite direction away from the blade. In order to convert the sharpening machine, Fig. 4, back into the safety 20 razor, after sharpening of the razor-blade, it merely requires to put back the guard 2 with the holding-plate 3 in place against the blade, Fig. 2, and disengaging the handle 7 from the projections 21 of frame 18 and engaging it with the projections 4 of said holding-plate.

Variations may be resorted to within the scope of the invention, and portions of the improvements may be used without others.

Having thus described our invention, we claim:-

1. A safety razor having the combination with a razor blade, and a guard therefor, of means projecting through said guard, an independent handle having means to spring over and engage said projecting means to secure said handle to said guard, a frame connected pivotally to said blade, said frame having means for springing over and engaging said handle therewith, and means to guide said blade angularly against a sharpening surface.

2. A safety razor having the combination with a razor blade, and a guard therefor, of means projecting through said guard, an independent handle having means to spring over and engage said projecting means to secure said handle to said guard, a frame connected pivotally to said blade, said frame having means for springing over and engaging said handle therewith, and means on said handle to guide said blade angularly against a sharpening surface.

3. A safety razor having the combination with a razor blade, and a guard therefor, of means projecting through said guard, an independent handle having means to spring over and engage said projecting means to secure said handle to said guard, a frame connected pivotally to said blade, said frame

having means for springing over and engaging said handle therewith, and a roller mounted on said handle for guiding said blade angularly against a sharpening surface.

4. A safety razor having the combination with a razor blade, and a guard therefor, of means projecting through said guard, an independent handle having means to spring over and engage said projecting means to secure said handle to said guard, a frame connected pivotally to said blade, means to maintain said blade in said frame against swinging, said frame having means for springing over and engaging said handle so therewith, and means to guide said blade angularly against a sharpening surface.

5. A safety razor having the combination with a razor blade, and a guard therefor, of a pair of connected projections passing through said blade and guard, a handle having a pair of spring-pressed extensions adaptable when pressed to slip over said projections and when released to spring over, and engage the projections to secure said handle to said guard, a frame connected pivotally to said blade, means to maintain said blade in said frame against swinging, said frame having a pair of projections, said handle adaptable to spring over and engage the projections of said frame, and means on said handle to guide said blade angularly against a sharpening surface.

6. A safety razor having the combination of a razor blade, a removable guard therefor, a removable handle, a frame connected pivotally to said blade, means to disengage said handle from said blade and guard and engage it with said frame, and means to guide said blade angularly against a sharpening surface.

7. A safety razor having the combination with a razor blade, a removable guard therefor, a removable handle, a frame connected pivotally to said blade, means to disengage said handle from said blade and guard and engage it with said frame, and means on said handle to guide said blade angularly against a sharpening surface.

8. A safety razor having the combination with a razor blade, a removable guard therefor, a removable handle, a frame connected pivotally to said blade, means to disengage said handle from said blade and guard and engage it with said frame, and a roller mounted on said handle for guiding said blade angularly against a sharpening surface.

9. A safety razor having the combination with a razor blade, a removable guard therefor, a removable handle, a frame connected pivotally to said blade, means to disengage said handle from said blade and guard and engage it with said frame, means to maintain said blade in said frame against swing-

ing, and means to guide said blade angularly against a sharpening surface.

10. A safety razor having the combination of a razor blade, a removable handle, a frame connected pivotally to said blade, means to disengage said handle from said blade and engage it with said frame, and means to guide said blade angularly against a sharpening surface.
- 10 11. A safety razor having the combination of a razor blade, a removable handle, a frame connected pivotally to said blade, means to disengage said handle from said blade and engage it with said frame, means to maintain said blade in said frame against swinging, and means to guide said blade angularly against a sharpening surface.
- 15

12. A safety razor having the combination of a razor blade, a frame connected pivotally to said blade, a handle for said frame, means to maintain said blade in said frame against swinging for applying the blade against a sharpening surface, and a roller mounted on said handle for guiding said blade and a handle at an angular inclination against a sharpening surface.

Signed at the city of New York, in the county of New York, and State of New York, this 10th day of May, A. D. 1915.
